DESIGN FOR A DILUTER FOR MOTOR CRANK CASE LUBRICANTS

Thomas Gallo, Arlington, Va.

Application October 26, 1942, Serial No. 108,613

Term of patent 3½ years

To all whom it may concern:

Be it known that I, Thomas Gallo, a citizen of the United States and a resident of Arlington, county of Arlington, State of Virginia, have invented a new, original, and ornamental Design for a Diluter for Motor Crank Case Lubricants, of which the following is a specification, reference being had to the accompanying drawings, forming part thereof.

Fig. 1 is a front elevational view of a diluter for motor crank case lubricants, showing my new design,

Fig. 2 is a side elevational view of one side of the diluter,

Fig. 3 is a top plan view thereof, and

Fig. 4 is a side elevational view of the side opposite to Fig. 2.

I claim:

The ornamental design for a diluter for motor crank case lubricants, as shown.

THOMAS GALLO.
